MODIFIED DUO-SOL REFINING

Harold C. Myers, Woodbury, N. J., assignor to Socony
Mobil Oil Company, Inc., a corporation of New York

Application April 25, 1952, Serial No. 284,255

11 Claims. (Cl. 196—14.2)

The present invention relates to "Duo-Sol" refining of mineral oil fractions of varying asphalt content and varying response to treatment when the refining operation is being carried out at the maximum rated capacity for the residuum being charged.

With the demand for high quality lubricating oils increasing and the cost of expanding refining facilities at a maximum, but held in check by various real or imposed shortages, it has become necessary to find some means for increasing the output of "Duo-Sol" units which are operating at rated maximum capacity. It has been found that the output of a "Duo-Sol" unit operating at maximum rated capacity can be increased to varying degrees dependent upon the character of available stocks and the point of introduction in the "Duo-Sol" unit of a secondary feed. Before discussing the application of the present invention to the problem it is considered desirable to discuss the physical system involved in a "Duo-Sol" extraction.

As those skilled in the art know, a "Duo-Sol" unit employs two solvents which *per se* are substantially immiscible. However, the solutions formed during the extraction of mineral oil fraction such as a residuum fraction may become of such character that the solutions of undesirable constituents in the solvent therefor become miscible with the solution of desirable constituents in the solvent therefor. This situation can be more readily understood and analyzed by reference to the two most commonly employed solvents, to wit: propane and "Selecto."

"Selecto" is a commercially available mixture of cresols and phenol usually containing from about 20% to about 65% phenol. "Selecto" dissolves from an oil, dark colored, low viscosity index constituents and resinous substances which are readily oxidized or carbonized in service.

Propane rejects asphaltic materials from an oil which, if present, would result in a high carbon residue, and low oxidation stability.

"Duo-Sol" extraction is conducted commercially in a unit which consists of a series of stages through which the propane and "Selecto" are passed counter-currently to each other in which each stage represents a single treating stage. The primary or sole feed is introduced into an extraction compartment or stage intermediate those used for charging the two solvents.

Referring now to Figure 1 which is a more or less diagrammatic representation of a "Duo-Sol" unit having 9 stages or cells or compartments. The oil to be treated is charged to compartment or cell No. 3 which thereby provides two propane washing stages for the "Selecto" extract (cells #1 and #2), and seven extraction stages for the propane solution of the charge oil (cells 3, 4, 5, 6, 7, 8 and 9).

The propane is introduced through line 35 to line 26 where it meets "Selecto" phase withdrawn from cell No. 2 through line 18, is mixed therewith and charged to cell No. 1. The "Selecto" is introduced through line 36 to line 34 where it meets propane phase withdrawn from cell No. 8 through line 17, is mixed therewith and charged to cell No. 9. The oil to be treated is introduced through line 39 to line 28 where it meets propane phase withdrawn from cell No. 2 through line 11 and "Selecto" phase withdrawn from cell No. 4 through line 20, is mixed there-

2

with and charged to cell No. 3. Extract, composed primarily of "Selecto" and the deleterious materials removed from the charge oil is removed from cell No. 1 through line 37 and sent to solvent recovery stills. Since the propane has a lower density than the "Selecto" there is a tendency to form an upper propane phase and a lower "Selecto" phase in each "Duo-Sol" unit cell. When the oil-Selecto-propane ratio is suitable such a separation into a propane phase and a "Selecto" phase takes place.

The propane phase from cell No. 1 passes through line 10 to line 27 where it is mixed with "Selecto" phase withdrawn from cell No. 3 through line 19. This mixture of propane and "Selecto" phases is introduced into cell No. 2 where a separation of propane and "Selecto" phases takes place, the propane phase passing through line 11 to line 28 where it is mixed with the charge stock as already described and the "Selecto" phase passes through line 18 to line 26 where it is mixed with charge propane as described.

One of the most important factors in the operation of a "Duo-Sol" unit is the establishment of conditions such as solvent ratio and ratio of each solvent to the volume of oil treated so that there is a separation of the two phases, i. e., propane phase and "Selecto" phase, sufficiently rapid in each stage to permit practical operation; stage No. 3 being particularly critical in this respect. In the remainder of the stages, or cells 4 to 9, phase separation occurs and the upper and lower phases move in opposite directions to effect a counter-current extraction of charge oil in propane solution with "Selecto." The propane phase from cell No. 3 moves through line 12 to line 29 where it meets "Selecto" phase from cell No. 5, is mixed therewith and passes into cell No. 4. Phase separation in cell No. 4 produces a "Selecto" phase which moves through line 20 to line 28 where it is mixed with charge stock as described heretofore. The propane phase from cell No. 4 moves through line 13 to line 30 where it meets the "Selecto" phase moving through line 22 from cell No. 6, is mixed therewith and passes into cell No. 5 for phase separation. Similarly, the propane phase from cell No. 5 passes through lines 14 and 31 to cell No. 6 while "Selecto" phase from cell No. 7 passes to cell No. 6 through lines 23 and 31. The propane phase of cell No. 7 passes through lines 16 and 33 to cell No. 8 while the "Selecto" phase from cell No. 9 passes through lines 25 and 33 to cell No. 8. The propane phase from cell No. 8 passes through line 17 to line 34 where it meets incoming fresh "Selecto," is mixed therewith and passes into cell No. 9. The propane phase of cell No. 9 passes out of the system as a solution of treated oil in propane to solvent recovery stills.

As those skilled in the art know, the determination of such physical and chemical properties as viscosity, gravity, viscosity-gravity constant, carbon residue and the like of a charge stock is not sufficient to enable even those who can be considered experts in the art of "Duo-Sol" refining to determine, *a priori*, the proper conditions for the treatment of a feed stock to produce a given quality raffinate. It is necessary with each charge stock or feed to make an extensive pilot plant investigation of the various factors, propane to "Selecto" ratio, propane and "Selecto" to oil ratio, extraction temperature and the like before commercial treatment of that particular feed can be attempted. However, once that investigation has produced the answers, those answers can be translated and transferred to commercial operation successfully.

When refining residua having moderate asphalt content, the effect of varying "Selecto" and propane ratios, "Selecto"-to-oil ratios and propane-to-oil ratios upon the yields and properties of the "Duo-Sol" treated oil (raffinate) is appreciable. The effect of such variations is illustrated by the graphs in Figures 2, 3, 4, 5 and 6.

In general, it can be said that with a given feed of moderate asphalt content the directional effect of the variation of solvent ratios upon the properties of a "Duo-Sol" raffinate is broadly indicated by the following tabulation:

"Selecto." Therefore, the relative effectiveness of the two solvents on the viscosity of the product depends largely upon the nature and quantity of the material which must be removed. The viscosity of oils of low asphalt content is more responsive to changes in "Selecto" dosage,

TABLE I

In addition to the effect produced by the variation of the variables discussed hereinbefore, the variables, number of extraction stages and extraction temperature also affect the results. Generally, the efficiency of the "Duo-Sol" treatment is increased by an increase in the number of extraction stages. Usually, increasing the extraction temperature has substantially the same directional effect as increasing the "Selecto" dosage at a constant propane dosage.

In general, the viscosity index (V. I.) of an oil is improved by the presence of asphaltic material and deteriorated by the presence of aromatic unsaturated bodies. In "Duo-Sol" refining, aromatic and unsaturated substances are effectively removed by solution in the "Selecto" while asphaltic substances are rejected by the propane. Therefore, the V. I. and V. G. C. of raffinates can be improved either by increasing the "Selecto" dosage or by decreasing the propane dosage, or by a combination of both. Improvement in V. I. or V. G. C. obtained by increasing the "Selecto" dosage or by decreasing the propane dosage is accompanied by a decrease in the yield of raffinate.

The yield of raffinate is virtually unaffected by increasing the amounts of both solvents while maintaining the ratio between them constant although the V. I. is decreased somewhat.

The carbon residue of the "Duo-Sol" treated oil reflects the quantity of asphaltic, resinous and thermally unstable aromatic and unsaturated substances present in the raffinate. In "Duo-Sol" refining the thermally unstable, resinous materials and asphalt are rejected to the "Selecto" phase and thereby removed from the system while the treated oil remains in the propane phase. As a consequence, the relative effectiveness of the two solvents for improving the carbon residue of the oil depends upon the type and quantity of carbon-forming materials which must be removed. The carbon residue of oils of low asphalt content is very responsive to change in "Selecto" dosage and less affected by alteration in propane dosage. Conversely, the carbon residue of oils of high asphalt content or asphaltic oils which are to be only lightly refined are more responsive to change in propane dosage.

The dark color associated with most residual oils is due largely to the presence of asphaltic and resinous materials. The relative decolorizing efficiencies of the two "Duo-Sol" solvents, therefore, depend on the nature and quantity of the dark colored materials present in the oil to be treated. The color of oils of low asphalt content is very responsive to change in "Selecto" dosage but less affected by alterations in propane dosage. Conversely, the color of oils of high asphaltic content is more responsive to change in propane dosage.

The viscosity can be altered by varying the quantity of asphaltic, resinous and high viscosity substances present in the oil to be treated. The asphaltic materials can be effectively rejected by the propane, while high viscosity and resinous components of the oil can be removed by the

while the viscosity of oils of high asphalt content is more responsive to changes in propane dosage.

In view of the foregoing, it is manifest that the variations in characteristics of the raffinate are dependent to a considerable degree upon the combination of temperature, "Selecto" dosage, propane dosage and "Selecto"-to-propane ratio, and to a minor extent upon the number of extraction stages. Consequently, it is necessary before going into commercial operation to go into the laboratory and determine the optimum conditions under which a raffinate of given characteristics can be produced from a given charge stock.

It has now been found that when a refinery "Duo-Sol" unit is operating at full capacity for a particular charge stock, a secondary feed can be introduced into the "Duo-Sol" unit, at some point other than the stage, cell or compartment into which the primary feed or the aforesaid charge stock is introduced, in an amount such that the total yield of raffinate from the treatment of the aforesaid charge stock or primary feed and the secondary feed will be increased considerably, without altering substantially the solvent dosages or solvent ratios employed when treating the particular charge stock or primary feed alone. In other words, under a given set of operating conditions when treating a particular charge stock, excess refining capacity exists not for the same charge stock but for a secondary charge stock of suitable characteristics. To achieve this increase in yield in a unit which, with respect to the primary feed, is operating at capacity, the characteristics of the primary feed and the characteristics of the secondary feed must be correlated.

By characteristics as used in this connection is meant the response to treatment and the content of asphaltic material in the mineral oil fraction to be used as secondary feed relative to the same characteristics of the primary feed.

As was mentioned hereinbefore, the physical and chemical characteristics which are usually determined on a feed stock such as carbon residue, gravity, viscosity, etc., are of little assistance in determining whether or not a secondary feed will be compatible with a primary feed. It is necessary to determine, preferably in the laboratory, the characteristics of the secondary feed either by a laboratory "Duo-Sol" treat or by a single solvent refining such as furfural extraction of the deasphalted secondary feed, whether the secondary feed will complement the primary feed or not. That is to say, when a "Duo-Sol" unit is treating the greatest volume of primary feed under given conditions from which a raffinate of given quality can be produced, the capacity of the unit for paraffinic material or for aromatic and asphaltic materials may be in excess of that utilized. In other words, the composition of the primary feed may be such that while the propane phase, relatively speaking, cannot hold any more paraffinic materials, the "Selecto" phase has excess carrying capacity under these conditions. Under such conditions a secondary feed of relatively low paraffinic oil content and

relatively high asphaltic content can be used as a secondary feed. On the other hand, the composition of a primary feed can be such that while the "Selecto" phase has limited capacity, relatively, for extracting additional non-paraffinic materials the propane phase has appreciable excess capacity relatively for holding paraffinic materials in solution without disturbing the settling conditions in the unit. Under these conditions, a relatively high paraffinic oil content stock low in asphaltic and other non-paraffinic constituents is suitable for use as a secondary feed.

While it would appear to be poor management to use more of one or both solvents than is required to achieve the particular extraction, the quantities and ratios of the solvents used are not solely dependent upon the amount of asphalt to be rejected nor upon the amount of non-paraffinic, non-asphaltic material to be extracted. The first limiting factor is the amount of each solvent required in the cell into which the feed is introduced to obtain a clean separation of the propane-oil phase from the "Selecto"-oil phase when treating the particular charge stock. Then the amount of each solvent must be adjusted to produce the quality of oil required from that particular unit treating that particular and closely similar charge stocks. Finally, other limitations must be considered. For example, a particular charge stock when treated with a given amount of propane and "Selecto" to yield an oil

10

15
20
25

reduction of the obtained color to the required color being beyond the capacity of the clay filtering plant used in conjunction with that particular "Duo-Sol" unit, it is necessary to obtain the required color by some other means. This problem can be solved by increasing the amount of propane used beyond that required to obtain the required V. I. and other characteristics of the oil. As a consequence thereof, an increased amount of propane is required to obtain the required color under the limitations of clay filtering capacity. Under these circumstances that "Duo-Sol" unit has excess capacity for a secondary feed which is of substantially the same responsiveness to treatment and of low to moderate asphaltic content.

For the purpose of illustrating the application of the present invention to the solution of the problem of increasing the yield of raffinate of given quality from a "Duo-Sol" unit operating at rated capacity on a given residuum, the treatment of a mixed residuum containing 20 vol. per cent Panhandle, 20 vol. per cent Oklahoma City, and 60 vol. per cent Apco-Pegasus residuum will be discussed. As secondary feed stocks Apco-Pegasus residuum, Pegasus residuum, Luling-Lytton Springs residuum, Kuwait propane deasphalted residuum, a heavy distillate and a light distillate are to be considered.

The charge stocks or feeds had the properties given in Table II.

Information on the solvent treatment of the various residual and distillate secondary feed stocks employed in modified "Duo-Sol" refining studies is included in Table III. These data show that Apco-Pegasus residuum, when treated with the same solvent dosages as the mixed residuum, produces a somewhat lower yield of a higher viscosity index raffinate than obtained by refining the mixed residuum. It would be concluded from this comparative information that Apco-Pegasus and the mixed residuum possess similar quality and asphalt content. Pegasus residuum, on the other hand, since it produces a much higher yield of a higher viscosity index raffinate than the mixed residuum when treated with the same quantities of solvent, would be adjudged of higher quality and lower asphalt content than the mixed residuum. Luling-Lytton Springs residuum, however, is apparently much lower in quality and higher in asphalt content than the mixed residuum since a high selecto dosage produces a low yield of only a 94 viscosity index product. Therefore, of these three stocks, Pegasus and Apco-Pegasus would be satisfactory secondary feeds for use with the mixed residuum while Luling-Lytton Springs would be considered unsuitable for use with this primary "Duo-Sol" charge stock.

Kuwait deasphalted oil and the light and heavy distillate stocks are known to be substantially asphalt-free. On the basis of "Duo-Sol" operation, the Kuwait oil appears similar in refining response to the Luling-Lytton Springs residuum and thus would be considered as a poor secondary feed stock for modified "Duo-Sol" operations with primary mixed residuum. The heavy distillate appears much poorer in quality than the Kuwait stock since treatment with a high furfural dosage only produces a low viscosity index product. This oil would also be an unsuitable secondary feed for use with the mixed residuum. The light distillate, however, provides a high yield of a 94/95 viscosity index oil when treated with a moderate furfural dosage and would therefore be considered about the same as or slightly inferior in quality to the Apco-Pegasus residuum as a secondary "Duo-Sol" feed stock.

From the foregoing, the primary feed (20% Panhandle, 20% Oklahoma City, 60% Apco-Pegasus) residuum

and the available secondary feed stocks can be classified with respect to response to treatment and asphalt content as follows:

TABLE IV

[Maximum +++++ Minimum 0]

	Stock	Relative Response to Refining	Relative Asphalt Content
Pegasus residuum	+++++	+	
P-O-A-P mixed residuum	++++	++	
Apco-Pegasus mixed residuum	+++	++	
Panhandle residuum	++	+	
Oklahoma City residuum	++	++	
Luling-Lytton Springs residuum	++		
Kuwait residuum	++	+++++	
Light Distillate	++	0	
Heavy Distillate	+	0	
Kuwait Propane Deasphalted residuum	++	0	

The mixed Apco-Pegasus-Oklahoma City-Panhandle residuum is classed as being of moderate to low asphalt content and of relatively high paraffinicity. From this point of view it would be normal to use relatively low "Selecto" and relatively low propane dosages for refining this oil. However, due to the additional need for producing products of satisfactory color in actual refinery practice, relatively low "Selecto" and relatively high propane dosages are actually used. This need for more propane than required for asphaltic constituent removal provides unused solvent capacity which can be utilized in treating a suitably selected secondary feed stock. (In general average "Duo-Sol" solvent dosages, expressed as weight per cent based upon the primary feed, are oil: 30 Selecto: propane=100:300:300 to produce a 95 V. I. oil while on the aforesaid mixed residuum the ratio is 35 100:175:425 to produce a 96 V. I. oil.)

The hereinbefore enumerated feeds were charged as secondary feeds to a "Duo-Sol" unit treating the rated capacity of the aforesaid Apco-Pegasus, Oklahoma City-Panhandle mixed residuum in the amounts indicated with the yields and qualities of raffinate indicated in Table V.

*Primary feed, Pegasus residuum.

"Sol" unit without increasing the amount of each solvent but employing an amount of each not less than that required to produce phase separation. In the usual operation of a 7 or 9 cell "Duo-Sol" unit the charge is introduced into the No. 3 cell; the phase separation conditions in this cell are controlling of the phase separation conditions of the unit. In the No. 3 or feed cell the bulk of the paraffinic components of the charge are separated from the non-paraffinic and asphaltic components thereof. In order to achieve phase separation, a minimum quantity of "Selecto" is necessary. Consequently, an increase in the amount of charge fed to the No. 3 cell without an

Referring now to the data presented in Table VI, run No. 1 yielded data on the solvent ratios necessary to produce a 96 V. I. oil having a 500 color. The oil- "Selecto"-propane ratio was 1:1.75:4.25. To those skilled in the art it is manifest that this operation involved the use of an unusually high proportion of propane to produce a light color product. Thus, in accordance with the principles of the present invention there is available excess propane capacity and a secondary feed of moderate or low-asphalt content can be used. Upon referring to the data presented in Table IV, it is manifest that Pegasus residuum is the most desirable stock

for use as a secondary feed because relative to Panhandle-Oklahoma City-Apco-Pegasus mixed residuum it is the most responsive to treatment and has a low asphalt content but Apco-Pegasus residuum of moderate asphalt content can also be employed. From the knowledge and experience gained in the "Duo-Sol" treatment of the primary feed and the rating of the secondary feed with respect to response to treatment and asphalt content it is determined that under steady operating conditions with the P-O-AP mixed residuum as a primary feed, Pegasus or Apco-Pegasus residua can be added to the No. 2 cell without increasing the amount of either solvent. The amount of secondary feed which can be introduced into the system can only be determined by investigation.

It will be noted that an amount of Pegasus residuum equivalent to 30% by volume or an amount of Apco-Pegasus residuum equivalent to 25% by volume can be introduced into the No. 2 cell with an increase in yield without adversely affecting either the V. I. or the color of the oil produced. However, if the same quantity of Apco-Pegasus residuum is introduced into the No. 3 cell the V. I. is reduced although the color remains satisfactory. (Run No. 3.) On the other hand, if the same quantity (25%) of Apco-Pegasus residuum is introduced into cell No. 5 rather than cell No. 3, the V. I. of the oil produced is unacceptable although the color is satisfactory. (Run No. 4.) While the secondary feed (Apco-Pegasus residuum) can be added in amounts up to 25% of the primary feed in cell No. 2 and cannot be added in that ratio to either cell No. 3 or cell No. 5 without deterioration of the oil obtained, a smaller quantity, i. e., 15% of the primary feed can be introduced into cell No. 5 without adversely affecting the quality of the oil. Similar effects can be obtained by charging the Pegasus residuum to the various compartments.

When the severity of the treatment is increased, as for example by reducing the quantity of propane employed which is the equivalent of increasing the concentration of "Selecto," the V. I. of the oil produced is satisfactory but the color is unsatisfactory. (Run No. 6.) Nor will the addition of secondary feed (Apro-Pegasus residuum) in a quantity equivalent to 25% of the primary feed into cell No. 3 and 15% of the primary feed into cell No. 5 for a total of 40% of the primary feed produce a satisfactory oil since the V. I. is unacceptable and the color is too high to be handled by the subsequent decolorizing unit. Since the limiting factor for this "Duo-Sol" plant handling Panhandle-Oklahoma City-Apco-Pegasus mixed residuum is the capacity of the clay decolorizing unit, the data presented in Table VI for runs Numbers 2, 3, 4, 5, 6 and 7 teach that for this combination of primary and secondary feeds, when employing as a secondary feed a stock which is most responsive to treatment and which has a minimum asphalt content relative to the primary feed, the secondary feed must be introduced into cell No. 2 for maximum yield of oil of the required quality without increasing the quantity of each solvent employed. However, run No. 5 discloses that with respect to the quality of the oil produced, this secondary feed can be introduced into cell No. 5 but only to the extent of about 60% of the amount that can be introduced into cell No. 2.

Thus, the capacity of the "Duo-Sol" unit under consideration for the primary feed under consideration can be increased in terms of S. A. E.-30 grade oil having a V. I. of 96 from 3760 barrels per stream day to 4650 barrels per stream day, an increase of 24%, by employing Apco-Pegasus residuum as the secondary feed. In other words, without expanding solvent recovery systems or darkening the color of the oil, without any addition to the "Duo-Sol" unit and with the same total quantity of each solvent the capacity of this "Duo-Sol" unit has been increased by 24% without any sacrifice of quality of the oil produced.

Referring now to runs Numbers 8, 9 and 10 it will be noted that a different residuum was used as the secondary feed. Pegasus residuum is more responsive to treatment and has slightly less asphalt than Apco-Pegasus residuum. As a consequence, it is not surprising that a greater quantity of Pegasus residuum can be introduced into cell No. 2 than Apco-Pegasus residuum without adversely affecting the quality of the oil produced. As a consequence, about 42% more S. A. E.-30, 96 V. I. oil can be produced without enlarging the treating equipment by introducing a quantity of Pegasus residuum equivalent to 30% of the primary feed as secondary feed into cell No. 2 of this "Duo-Sol" unit.

Luling-Lytton Springs residuum is a stock which is appreciably less responsive to treatment than either Pegasus or Apco-Pegasus residua, but has about the same asphalt content as Apco-Pegasus residuum and slightly more asphalt than Pegasus residuum. Consequently Luling-Lytton Springs residuum cannot be added in as great a quantity as a secondary feed to cell No. 2 as either Apco-Pegasus or Pegasus residuum to produce a 96 V. I. quality oil. It will be noted (run No. 11) that at a level of 15% of the primary feed the oil produced has a very satisfactory color but the V. I. (95) is not acceptable.

It is of interest to consider the potentiality of light and heavy distillate from a different crude as secondary feeds in this operation; runs Numbers 13 through 20 provide a spectrum of results. When this light distillate (substantially devoid of asphalt) is introduced into cell No. 5 in amounts equivalent to 25% to 40% of the primary feed the oil produced is not satisfactory as to V. I. (94-95) and is of barely acceptable color. However, when introduced into cell No. 5 in a quantity equal to about 15% of the primary feed the oil produced is satisfactory with respect to V. I. (96) and color (425). In contrast, when the heavy distillate is introduced into cell No. 5 in a quantity equal to about 15% of the primary feed the oil produced is not acceptable with respect to V. I. (93) although of satisfactory color. When the severity of the treatment is increased and a quantity of heavy distillate equal to 15% of the primary feed is introduced into cell No. 2 the V. I. is improved although still unsatisfactory when the goal is an oil of 96 V. I. but the color is sufficiently low that the oil can be treated in the clay filtering facilities available. When the severity of the treatment is further increased by a further reduction in the propane used, the oil produced is satisfactory from the standpoint of V. I. (96) but the color is unacceptable because of clay filtering limitations.

Considering runs Numbers 21 through 23 wherein Kuwait propane deasphalted residuum was used as a secondary feed, it will be noted that, at a level of 15% of the primary feed, introduction of this propane deasphalted residuum into cell No. 5 yields an oil which is not satisfactory from the standpoint of V. I. Thus, for use in conjunction with this primary feed this deasphalted oil is not a suitable secondary feed although this deasphalted oil would be a suitable secondary feed to be used in conjunction with a primary feed whose response to treatment is more similar to that of this deasphalted oil.

Upon referring to runs Numbers 24 and 25, it will be noted that under the designation, run No. 24, the significant data for the treatment of Pegasus residuum are collected. The yield of 4670 barrels of S. A. E.-30 oil per stream day combined with the relatively high V. I. of 98 indicate that Pegasus residuum is more responsive to treatment than the Panhandle-Oklahoma City-Apco-Pegasus residuum. The data presented for run No. 25 establish that the yield of S. A. E.-30 oil can be increased more than 62% when employing the 97 V. I. bright stock produced by using 25% Pegasus residuum as a secondary feed. However, if the Pegasus residuum introduced into cell No. 2 in run No. 25 were introduced into cell No. 3, the conditions necessary for phase separation in cell

No. 3 would be changed and a poor phase separation result.

The data presented in Table VI therefore represent the treatment of two residua which are very responsive to treatment wherein the variable limiting the type and quantity of secondary feed when used with either of the primary feeds is the capacity of the clay filtering plant to decolorize the "Duo-Sol" raffinate. Because of this limited capacity the propane dosage is high. As a consequence of the high propane dosage, the quantity of "Selecto" employed to produce satisfactory phase separation in cell No. 3 is more than required to produce the desired refining effect upon the primary feeds. Accordingly, there is an excess of refining capacity. Therefore, a primary feed of substantially the same response to treatment and having a low to moderate asphalt content can be introduced as a secondary feed into the No. 2 cell in relatively large quantities without an increase in the quantity of either propane or "Selecto" to produce an oil of substantially the same quality as produced when treating the primary feed alone.

The following tabulation of data obtained when operating upon a primary stock of different response and a secondary feed of substantially the same response as the primary charge illustrates another phase of the situation. The primary feed was a Kuwait residuum of substantial asphalt content and moderate response to treatment and the secondary feed was a Kuwait propane deasphalted residuum. The primary feed when treated at a 1:2.5:3, oil—"Selecto"-propane ratio was charged at the maximum rate for the particular "Duo-Sol" unit and its auxiliary equipment and the equipment of the sequential operations of that refinery to produce a 98 V. I. oil.

TABLE VII
[Primary feed—Kuwait residuum.]

	Run Number	
	26	27
Secondary Feed, percent	None	50
Cell Number		2
Oil—"Selecto"-propane, ratio	1:2.5:3	1:2.5:3
V. I.	98	100
Color	83	61
S. A. E.-30 B/SD	100	165
Relative S. A. E.-30 Production, percent	100	158

Reference to Table IV will establish that Kuwait residuum gives moderate response to treatment and has a high asphalt content. Propane deasphalted Kuwait residuum gives moderate response to treatment and is substantially devoid of asphalt. Thus, the secondary feed had substantially the same response to treatment but no asphalt. When the two feed stocks were treated simultaneously without increasing the quantity of either solvent over that employed for refining the primary feed alone, a high grade oil was obtained and the yield of S. A. E.-30 oil was increased by 65% without any increase in plant facilities.

Thus, there has been provided hereinbefore two examples of different conditions which can be encountered in "Duo-Sol" treating and of the solutions thereto with increased yield of the same quality oil without increasing the amount of either solvent or the total amount of both solvents and without increasing plant facilities. In other words, the increased yield of oil of required quality is gotten practically at no cost to the refiner.

Accordingly, the present invention is that improvement in "Duo-Sol" operation which comprises selecting a secondary feed having a response to treatment complementary to that of the primary feed and introducing said secondary feed into cells No. 1 or No. 2 or No. 4 or No. 5 or No. 6 or No. 7 or No. 8 depending upon (1) excess propane capacity or excess "Selecto" capacity, (2) response to treatment compared to the primary feed and

(3) asphalt content, and without increasing the quantity of either solvent over that required for the primary feed or the total quantity of solvent but with sufficient of both solvents to produce a phase separation in the cell into which the primary feed is introduced, treating both primary and secondary feeds simultaneously to produce an oil of at least equal quality to that of the oil produced from the primary feed alone under the same conditions of solvent ratio and treating temperature.

We claim:

1. In the "Duo-Sol" method of refining mineral oil comprising paraffinic and non-paraffinic constituents which comprises extracting in a plurality of stages an oil comprising paraffinic and non-paraffinic constituents with a refining solvent in the presence of an added liquid having greater solvent power for paraffinic constituents of said oil than for non-paraffinic constituents of said oil, said solvent for paraffinic constituents of said oil and said refining solvent being adapted to form a two liquid phase solvent system, the improvement which comprises selecting a secondary feed other than the aforesaid oil having a response to treatment complementary to that of said oil and of no greater asphalt content than said oil and, whilst the flow rates of said added liquid and said refining solvent remain substantially unaltered and whilst continuing to introduce the aforesaid oil at a maximum rate concomitant with producing in maximum yield a raffinate of required quality, introducing said secondary feed into said "Duo-Sol" system at a point other than the point of introduction of said oil intermediate the initial stage and the final stage dependent upon the relative response to treatment and asphalt content as previously determined, and the more responsive said secondary feed is to treatment relative to said oil the nearer the first stage said secondary feed is introduced to produce a maximum yield of oil of required quality.

2. In the art of refining mineral oil in which an oil comprising paraffinic and non-paraffinic constituents as a primary feed is extracted with a solvent having greater solvent power for non-paraffinic constituents in the presence of an added liquid having greater solvent power for paraffinic constituents in a counter-current system having a plurality of stages, said solvents being adapted to form a two liquid phase solvent system, the improvement which comprises selecting a secondary feed other than said primary feed having a response to treatment complementary to that of a primary feed, whilst introducing said primary feed at a maximum rate concomitant with a maximum yield of a raffinate of required quality, introducing said secondary feed into a cell other than that into which said primary feed is introduced intermediate the initial and final cells of the system dependent upon the response of said secondary feed relative to the response of said primary feed to treatment, and to produce a maximum yield of oil of required quality the more responsive said secondary feed is relative to said primary feed, the nearer the first stage said secondary feed is introduced, and without increasing substantially the amount of either solvent but with an amount of each solvent sufficient to produce phase separation in the cell into which said primary feed is introduced, treating said primary feed and said secondary feed simultaneously to produce a raffinate of substantially the same quality as produced when treating said primary feed.

3. A method of refining mineral oil which comprises establishing a refining system having a plurality of stages, introducing as a primary feed an oil having paraffinic and non-paraffinic constituents into a stage intermediate the initial stage and the final stage of said system, introducing into the initial stage a solvent having greater solvent power for paraffinic than for non-paraffinic constituents of said oil, introducing into the final stage a solvent having greater solvent power for non-paraffinic than for paraffinic constituents of said oil, both of said solvents being adapted to form a two liquid phase solvent system and being in-

roduced in quantities and in a ratio to separate said oil into a raffinate having a required V. I. and an extract, establishing equilibrium conditions in said refining system whereby a given yield of oil of required quality is produced, selecting a secondary feed other than said primary feed having a response to treatment complementary to that of said primary feed, introducing said secondary feed into a stage other than that into which said primary feed is introduced intermediate said initial stage and said final stage, and without increasing substantially the quantity of either solvent and without reducing the quantity of said primary feed introduced into said refining system substantially simultaneously refining said primary feed and said secondary feed to produce an increased yield of oil of at least said required quality.

4. In the method of refining oil to produce a raffinate more paraffinic than the charge stock and an extract more non-paraffinic than the charge stock which comprises establishing a refining system having a plurality of stages, introducing as a primary feed an oil having paraffinic and non-paraffinic constituents into a stage intermediate the initial stage and the final stage of said system, introducing into the initial stage of said system a solvent having greater solvent power for said paraffinic than for said non-paraffinic constituents of said oil, introducing into said final stage a solvent having greater solvent power for said non-paraffinic than for said paraffinic constituents of said oil, said solvents being adapted to form a two liquid phase solvent system, flowing said solvents in counter-current manner through said system in contact with said oil in amounts and in a ratio to refine said oil to produce a maximum yield of a raffinate of required quality, selecting a secondary feed other than said primary feed having a response to treatment complementary to that of said oil, without increasing the amount of either solvent and without reducing the amount of primary feed introduced into said refining system introducing said oil as a primary feed into said stage intermediate said initial and final stages and introducing said selected secondary feed into a stage other than that into which said primary feed is introduced intermediate said initial and final stages dependent upon the response of said secondary feed to treatment relative to said primary feed and in amount sufficient to produce an increased yield of oil of at least said required quality and substantially simultaneously treating said primary and secondary feeds to produce an increased yield of oil of at least said required quality.

5. In the method of refining mineral oil which comprises establishing a refining system having a plurality of stages, introducing into the initial stage thereof a first solvent having greater solvent power for paraffinic than for non-paraffinic constituents of a mineral oil, introducing into the final stage thereof a second solvent having greater solvent power for non-paraffinic than for paraffinic constituents of a mineral oil, introducing as a primary feed into a stage intermediate said initial and final stages a mineral oil having paraffinic and non-paraffinic constituents, the ratio of oil to first solvent to second solvent by weight being within the limits 1:1:1 to 1:7:7 and said solvents being adapted to form a two-liquid phase solvent system, flowing said solvents in counter-current manner through said system in contact with said oil in amounts and in a ratio to produce a raffinate of required quality and recovering a raffinate of required quality, the improvement of which comprises selecting a secondary feed having a response to treatment complementary to that of said oil, continuing to introduce at a maximum rate concomitant with a maximum yield of raffinate of said required quality said oil as a primary feed to said stage intermediate said initial and final stages without increasing the quantity of either solvent, introducing said selected secondary feed into a stage other than that into which said primary feed is introduced intermediate said initial and final stages dependent upon the response of said feed to treatment relative to said primary feed and in amount

sufficient to increase the yield of oil of at least required quality, and simultaneously refining said primary feed and said secondary feed to produce an increased yield of oil of at least required quality.

- 5 6. A method of refining mineral oil which comprises establishing a refining system having a plurality of stages, introducing into a stage intermediate the initial stage and the middle stage thereof a charge oil having paraffinic and non-paraffinic constituents, into the initial stage thereof 10 propane and into the final stage thereof "Selecto" said "Selecto" comprising a mixture of cresols and phenol containing about 20 to about 65 per cent phenol, adjusting the quantities of oil, propane and "Selecto" to produce a maximum yield of refined oil of required quality from 15 said refining system, determining that under steady conditions of maximum yield of refined oil of required quality from said charge oil there is excess of propane refining capacity, introducing a secondary feed having a response to treatment complementary to said charge oil into a stage 20 intermediate the stage into which said primary feed is introduced and the final stage of said refining system, maintaining an oil : "Selecto" : propane ratio substantially no greater than that employed when treating said charge oil as the sole feed to said refining system, adjusting the 25 amount of secondary feed to produce an appreciably increased yield of oil of at least required quality, and refining said charge oil and said secondary feed simultaneously to produce an appreciably increased yield of oil of at least required quality.
- 30 7. A method of refining mineral oil which comprises establishing a refining system having a plurality of stages, introducing into a stage intermediate the initial stage and the middle stage thereof a charge oil having paraffinic and non-paraffinic constituents, into the initial stage thereof 35 propane and into the final stage thereof "Selecto" said "Selecto" comprising a mixture of cresol and phenol containing about 20 to about 65 per cent phenol, adjusting the quantities of oil, "Selecto" and propane to produce a maximum yield of refined oil of required quality from 40 said refining system, selecting a secondary feed other than said charge oil having a response to treatment complementary to that of said charge oil, introducing said selected secondary feed into a stage other than that into which said charge oil is introduced intermediate said initial and final stages of said refining system whilst continuing to introduce said charge oil at the same rate and said propane and "Selecto" at substantially no greater rate 45 than before introducing said secondary feed and regulating the stage of introduction and the rate of introduction 50 to produce a refined oil of at least required quality, and treating said charge oil and secondary feed to produce an appreciable increased yield of refined oil of at least required quality.
8. A method of refining mineral oil which comprises 55 establishing a refining system having a plurality of stages in excess of three, introducing a first solvent having a greater solvent power for paraffinic than for non-paraffinic constituents of a hydrocarbon oil into the first stage of said refining system, introducing a second solvent having 60 greater solvent power for non-paraffinic than for paraffinic constituents of hydrocarbon oil into the final stage of said refining system, introducing as a primary feed a hydrocarbon oil having paraffinic and non-paraffinic constituents into a stage intermediate the initial and middle stages of 65 said refining system, regulating the rate of flow of said primary feed, said first solvent and said second solvent to form a two-liquid phase solvent system and to produce a maximum yield of a raffinate of required quality at the maximum rate of flow of said primary feed whereby the capacity of said first solvent to dissolve further amounts of paraffinic constituents is substantially limited, while the capacity of said second solvent to dissolve further quantities of non-paraffinic constituents is in excess of that required, whilst continuing to introduce said primary feed 70 at said maximum rate of flow and without substantially 75

altering the rates of flow of said first and second solvents, introducing into said refining system at a point other than that at which said primary feed is introduced and intermediate said initial stage and the stage next after the middle stage and in quantity sufficient to appreciably increase the yield of raffinate of at least the required quality a secondary feed comprising a hydrocarbon oil of low paraffinic constituent content and high asphaltic constituent content relative to said primary feed and simultaneously refining said primary feed and said secondary feed to produce a raffinate of at least required quality in excess of the maximum amount of raffinate obtainable at the maximum rate of flow of said primary feed.

9. In a "Duo-Sol" refining system having a plurality of stages in excess of three wherein a primary feed is being treated at maximum rate of flow with a fixed volume of a first solvent having greater solvent power for paraffinic than for non-paraffinic constituents of said primary feed and with a fixed volume of a secondary solvent having greater solvent power for non-paraffinic than for paraffinic constituents of said primary feed and said first and second solvents are introduced in a mutually fixed ratio to produce a raffinate of required quality at maximum yield for said primary feed said "Duo-Sol" refining system having excess capacity for paraffinic constituents of a secondary feed or excess capacity for non-paraffinic constituents of a secondary feed the improvement which comprises continuing to introduce said primary feed at the aforesaid maximum rate of flow whilst maintaining the aforesaid fixed rates of flow of said first and second solvents, introducing a secondary feed, other than the aforesaid primary feed, and having a response to treatment complementary to that of the aforesaid primary feed into stages other than those into which the aforesaid primary feed and the aforesaid second solvent are introduced dependent upon (1) which solvent capacity is in excess, (2) response to treatment compared to that of the aforesaid primary feed and (3) asphalt content, and withdrawing a raffinate of the aforesaid required quality in substantially increased amount.

10. A method of refining a mineral oil which comprises establishing a refining system having a plurality of stages in excess of three, introducing into the initial stage of said refining system a first solvent having a greater solvent power for paraffinic than for non-paraffinic constituents of a hydrocarbon oil, introducing into the final stage of said refining system a second solvent having greater solvent power for non-paraffinic than for paraffinic constituents of a hydrocarbon oil, introducing into a stage intermediate the first and the middle stage of said refining system a primary feed comprising a hydrocarbon oil having paraffinic and non-paraffinic constituents, regulating the flow of oil of said first solvent and said second solvent to form a two-liquid phase system and to provide maximum flow of said primary feed into said refining system with the production of a maximum quantity of a raffinate of required quality whereby the capacity of said first solvent to dissolve further amounts of paraffinic constituents is in excess of that required while the capacity of said second solvent to dissolve further amounts of non-paraffinic constituents

is substantially limited, whilst continuing to introduce said primary feed at a maximum rate of flow and without substantially altering the rates of flow of said first and said second solvents, introducing into said refining system at a point intermediate the stage into which said primary feed is introduced and the final stage of said refining system a secondary feed comprising a hydrocarbon oil having a paraffinic constituent content high and a non-paraffinic constituent content low relative to the said primary feed in an amount sufficient to produce an appreciable increase in the yield of raffinate of at least required quality, and refining said primary feed and said secondary feed simultaneously to produce an appreciably increased yield of raffinate of at least required quality.

11. In the method of refining mineral oil which comprises establishing a refining system having a plurality of stages in excess of three, introducing into the initial stage thereof a first solvent having greater solvent power for paraffinic than for non-paraffinic constituents of mineral oil, introducing into the final stage thereof a second solvent having greater solvent power for non-paraffinic than for paraffinic constituents of a mineral oil, introducing into a stage intermediate said initial and final stages as a primary feed a mineral oil having paraffinic and non-paraffinic constituents, the ratio of oil to first solvent to second solvent by weight being within the limits 1:1:1 to 1:7:7, and said first and second solvents being adapted to form a two-liquid phase solvent system, flowing said solvents in counter-current manner through said refining system in contact with said oil in amounts and in a ratio to produce a raffinate of required quality, increasing the rate of flow of said primary feed, said first solvent and said second solvent until a maximum rate of flow of said primary feed into said refining system at which a maximum yield is attained of raffinate of required quality, whilst the rates of flow of said first and second solvents remain substantially unaltered continuing to introduce said primary feed at said maximum rate of flow whilst introducing into a stage other than that into which said primary feed is introduced a secondary feed other than said primary feed and having a response to treatment complementary to that of said primary feed, said secondary feed being introduced into a stage intermediate said initial and final stages dependent upon the response of said feed to treatment relative to said primary feed, said secondary feed being introduced into said refining system in an amount sufficient to increase appreciably the yield of raffinate of at least required quality, and simultaneously refining said primary feed at maximum rate of flow and said secondary feed to produce an increased yield of raffinate of at least required quality.
